[57] CLAIM

The ornamental design for radio receiver, as shown and described.

DESCRIPTION

FIG. 1 is a top plan view of a radio receiver showing my new design;

FIG. 2 is a left-side elevational view thereof;

FIG. 3 is a front elevational view thereof;

FIG. 4 is a right-side elevational view thereof;

FIG. 5 is a bottom plan view thereof;

FIG. 6 is a rear elevational view thereof;

FIG. 7 is a top, front and right-side perspective view thereof;

FIG. 8 is a top, front and right-side perspective view thereof with the top being shown in its closed position; and,

FIG. 9 is a front elevational view thereof in operating condition.

The broken line showing on FIG. 9 is for illustrative purposes only and forms no part of the claim design.
